UNITED STATES PATENT OFFICE.

ROBERT M. DE VIGNIER, OF HOLLIS, NEW YORK, AND BRUCE FREILE, OF BOGOTA, NEW JERSEY, ASSIGNEES TO WESTERN ELECTRIC COMPANY, INCORPORATED, OF NEW YORK, N. Y., A CORPORATION OF NEW YORK.

CIRCUIT-CONTROLLING SWITCH.

1,295,709.

Specification of Letters Patent.

Patented Feb. 25, 1919.

Application filed July 16, 1918. Serial No. 245,163.

To all whom it may concern:

Be it known that we, ROBERT M. DE VIGNIER and BRUCE FREILE, a citizen of the United States and a subject of the King of Great Britain, respectively, residing at Hollis, in the county of Queens, State of New York, and at Bogota, in the county of Bergen, State of New Jersey, respectively, have invented certain new and useful Improvements in Circuit-Controlling Switches, of which the following is a full, clear, concise, and exact description.

This invention relates to a circuit controlling switch, and its object is to provide a simple, compact, inexpensive and efficient device which will be adapted to control a large number of independent electrical circuits.

The device, which is termed an interrupter, consists of a rotatable spindle to which a cam and a gear are rigidly secured, a motor mechanism for operating the rotary elements, a movable bar arranged to be operated by the rotation of the cam, and a series of movable switch-members arranged to be operated by the movement of the bar. The movable switch-members to be operated are contact springs mounted upon, but insulated from, the supporting frame in which the spindle is mounted.

The motor mechanism for operating the movable elements of the interrupter preferably consists of a continuously rotating power shaft common to a plurality of interrupters and a pinion carried by the power shaft arranged to mesh with the gear on the spindle. With this arrangement it will be observed that each interrupter is a unit and can be driven at any desired speed independent of the other interrupters driven from the same driving shaft, simply by changing the ratio of the pinion and driven gear.

The bar which operates the contact springs is supported by two flat springs, which render the use of pivots unnecessary and serve to keep the bar in engagement with the cam at all times.

Referring to the drawing, Figure 1 is a top view of an interrupter constructed in accordance with this invention, and Fig. 2 is a front view of said interrupter.

The supporting frame 1 of the interrupter is provided with three flanges 2, 3 and 4 by

means of which the frame 1 may be fastened to a flat surface by the screws 5, 6 and 7 respectively. One end of the frame 1 has a forwardly projecting yoke. A spindle 8 is rotatably mounted in bearings 9 and 10 in the arms 11 and 12 respectively of the yoke. Between the arms 11 and 12 a collar 14 is fastened to the spindle 8 by a set screw 29. A gear 13 is rigidly secured to the collar 14 in any well known manner. The gear 13 meshes with a pinion 17 which is secured to a constantly rotating shaft 18. A cam 15 is rigidly secured to the collar 14 and the gear 13 by screws 16 which extend through the cam and collar.

The spindle 8, cam 15, collar 14 and gear 13 rotate as a complete unit. To assemble this unit, the cam 15 is first fastened to the collar 14 and the gear 13. Then this assembled portion of the unit is placed between the arms 11 and 12 of the yoke. The spindle is next inserted and then the collar is fastened thereto by the set screw 29. The width of the collar together with the width of the cam and the gear is the same as the distance between adjacent faces of the arms 11 and 12. Therefore after the rotary unit is completely assembled no axial movement of the spindle can take place.

A bar 20 carrying a roller 21 at one end thereof, is supported by two flat springs 22 and 23, one end of each spring being attached to the frame 1 and the other end of each spring being attached to the bar 20. The bar 20 is arranged so that these springs 22 and 23 keep the roller 21 of the bar in engagement with the surface of the cam 15. The bar 20 is provided with two rows of pins 24 of insulating material, one row extending longitudinally along the top of the bar 20 and the other row extending longitudinally along the bottom of the bar 20.

A plurality of sets of contact springs 19 are arranged in a row along the top of the frame 1 and are secured thereto in any well-known manner. A similar row is secured to the bottom side of the frame 1.

Each pin 24 in the row on the top side of the bar 20 is in operative relation with a different set of contact springs of the row attached to the top side of the frame 1. Similarly each pin 24 in the row on the bottom side of the bar 20 is in operative relation with a different set of contact springs of the

row attached to the bottom side of the frame 1.

This arrangement is such that as the cam 15 is rotated the bar 20 is longitudinally moved back and forth. This movement of the bar 20 is sufficient to cause the pins 24 to open and close the contact springs 19. It will therefore be obvious that if the shaft 17 rotates at a constant speed the circuits 10 through the contact springs 24 will all be interrupted at a constant rate. Also it will be obvious that this rate may be readily changed by merely changing the ratio between the pinion 17 and the gear 13.

15 What is claimed is:

1. In combination, a frame, a rotatable cam mounted therein, a bar arranged to be moved longitudinally by the rotation of said cam, a row of pins on said bar, and a row 20 of sets of contact springs mounted on said frame, each pin on said bar being in operative relation with a particular set of contact springs.

2. In combination, a frame, a rotatable cam mounted therein; a bar arranged to be 25 moved longitudinally by the rotation of said cam, a plurality of rows of pins on said bar, and a plurality of rows of sets of contact springs mounted on said frame, the pins in each row being in operative relation with the sets of contact springs in a particular row.

3. In combination, a frame, a rotatable cam mounted therein, a row of sets of contact springs, a longitudinally movable bar having a pin in operative relation with each individual set of contact springs, and a plurality of flat flexible springs rigidly attached to said frame and bar for supporting said bar and for maintaining it in engagement with the surface of said cam.

In witness whereof, we hereunto subscribe our names this 8th day of July, A. D. 1918.

ROBERT M. DE VIGNIER.
BRUCE FREILLE.
